UNITED STATES PATENT OFFICE

149,793

DESIGN FOR A SUPPORT BRACKET FOR OVER-BED TABLE

Francis J. Burst, Batesville, Ind., assignor to Hill-Rom Company, Inc., Batesville, Ind., a corporation of Indiana

Application June 4, 1946, Serial No. 130,392

Term of patent 14 years

(Cl. D33—14)

To all whom it may concern:

Be it known that I, Francis J. Burst, a citizen of the United States, residing at Batesville, in the county of Ripley and State of Indiana, have invented a new, original, and ornamental Design for a Support Bracket for Over-Bed Table, of which the following is a specification, reference being had to the accompanying drawing, forming a part thereof.

Figure 1 is a perspective view of the new bracket showing it in position relative to the table, the table being shown in dot and dash lines for illustrative purposes only.

Figure 2 is the side view of the bracket.

Figure 3 is the end view thereof.

Figure 4 is a top plan view thereof.

I claim:

The ornamental design for a support bracket for over-bed table, substantially as shown and described.

FRANCIS J. BURST.
